UNITED STATES PATENT OFFICE.

ROBERT H. BEAUMONT, OF RADNOR, PENNSYLVANIA, ASSIGNOR TO BEAUMONT MANUFACTURING COMPANY, OF PHILADELPHIA, PENNSYLVANIA, A CORPORATION OF NEW JERSEY.

ASH HOPPER FOR BOILERS.

Application filed January 2, 1924. Serial No. 683,859.

The principal objects of the present invention are, first, to avoid corrosion and for that purpose to eliminate structural steel; second, to facilitate the use of cast iron and to that end to avoid the use of special angular connections; third, to meet the requirements of various boiler houses by the use of standard castings with slight exceptions which involve merely differences in length 10 of the cast iron hangers which form part of the structure; and fourth, to provide an adjustable cast iron hopper structure of which one end is of any standard gate size and shape and of which the other end is of variable 15 size and shape for application in different boiler houses with merely the substitution of elements of differing and appropriate lengths. Other objects of the invention will appear from the following description 20 and it may be said that the invention, generally stated, comprises an ash hopper for boilers comprising a gate structure provided with cast iron hangers having at one of the ends thereof articulated connection with the 25 gate and having at the other of the ends thereof articulated suspension supports and a lining carried by the hangers. The invention also comprises the improvements to be presently described and finally claimed.

30 In the following description reference will be made to the accompanying drawings forming part hereof and in which

Figure 1 is an elevational view of an ash hopper embodying features of the invention 35 showing parts in section.

Fig. 2 is a top or plan view of one-half of the same with the lining omitted, and

Fig. 3 is an elevational view, partly in section, illustrating an intermediate hanger adjustable as to effective length and embodying a modification of the invention.

In the drawings 1 is a gate frame, and 2 is a gate arranged to co-operate with the frame 1 and shown as mounted on rails 3. 45 The frame 1 is shown as generally rectangular and it is provided with articulated hangers. The hangers 4 operate as buckstays and the hangers 5 are valley or corner pieces. The hangers 4 are connected with the gate frame by hinges 6, and the hangers or corner pieces 5 are connected with the gate frame by ball and socket or universal joints 7. The upper ends of the hangers 4 are provided with suspension supports 8, connected there-

to by hinge elements 9 and 13, and the upper ends of the hangers 5 are provided with suspension supports 10 connected thereto by ball and socket or universal joints 11. 12 is a lining carried by the hangers and it may consist of a monolith or of a number of tiles. 55

In installing for use the suspension supports 8 and 10 are secured to a boiler housing or structure the shape of the opening in which determines their position and the articulations at the ends of the hangers permit them to assume whatever inclination may be required by reason of the constant size and shape of an appropriate stock gate frame 1 and by the particular size and shape of the opening at the inlet of the hopper, and the 70 lining, being of tile work, is cut to fit. Obviously in some cases hangers of different lengths will be required to meet the peculiar conditions of size and shape of the inlet of the hopper due to the construction of the 75 boiler house. Within limits the lengths or effective lengths of the hangers can be adjusted by means of the nuts and threaded stems 15, Fig. 1, or 16, Fig. 3, and in such cases all of the parts are standard. Beyond 80 those limits it may be necessary to substitute hangers of different lengths, but otherwise the parts, including the gate frame and the articulations and the suspension supports, are selected from standard stock. The lining 85 is cut to fit. The result of this is that the structure is peculiarly adapted to be made of cast iron which resists corrosion and that is a very important matter in ash hoppers for boilers. It may be remarked that the 90 pins 13 and the connections 14, 15 and 16 are separate from the rest of the structure so that very few patterns have to be provided. The differences in angular disposition of the hangers in respect to the parts with which 95 they are connected are compensated for by the articulations and adjustments when present at the ends of the hangers. In a general way the structure may be regarded as made up of a base of fixed dimensions and a top 100 of variable dimensions by reason of the articulations at the ends of the hangers. A change in size or shape of the openings at the inlet or outlet, or requirements of height or depth, may necessitate the use of hangers 105 or of some hangers of different lengths, but such hangers are cheaply provided and are only necessary where the changes of length

required exceed the limits of the adjustments 15 and 16.

It will be obvious to those skilled in the art to which the invention relates that modifications may be made in details of construction, arrangement and matters of mere form without departing from the spirit of the invention which is not limited as to such matters or otherwise than as the prior art 10 and the appended claims may require.

I claim:

1. An ash hopper structure for boilers of which the outlet at the base consists of a gate frame of standard size for different 15 installations and which is provided with hangers hingedly connected with the frame and provided with hingedly connected suspension supports adopted for installation with inlet openings of different sizes in different installations, and said hangers provided with means for adjusting their effective length.

2. An ash hopper and gate structure comprising in combination a gate frame, cast 25 iron hangers having hinged articulation with the gate frame, suspension supports having hinged articulation with the hangers, and a lining carried by the hangers.

3. An ash hopper for boilers comprising a gate structure, valley corner hangers having 30 ball and socket connection with the gate structure, intermediate hangers hingedly connected with the gate structure, a lining carried by the hangers, and suspension supports of which some are hingedly connected to the intermediate hangers and of which others have ball and socket connection with the valley hangers.

4. An ash hopper structure for boilers provided with hangers, a gate structure having hinged articulation with the hangers at one of the ends thereof and constituting an outlet of fixed size and shape, and suspension supports having hinged articulation with the other of the ends of the hangers, 40 whereby the inlet of the hopper may be of different size and shape.

5. An ash hopper and gate structure comprising in combination a gate frame, cast 45 iron hangers having hinged articulation with the frame, suspension supports having hinged articulation with the hangers, and adjusting means for changing the effective lengths of the hangers.

ROBERT H. BEAUMONT.
